CLAIM

I claim, the ornamental design for the glass urn, as shown and described.

DESCRIPTION

FIG. 1 is a front elevational view of the glass urn showing my new design;

FIG. 2 is a rear elevational view of the glass urn thereof;

FIG. 3 is a left-side elevational view of the glass urn thereof;

FIG. 4 is right side view of the glass urn thereof;

FIG. 5 is a top plan view of the glass urn thereof; and,

FIG. 6 is a bottom plan view of the glass urn thereof.

The broken line showing of the text is included for the purpose of illustrating environmental structure and forms no part of the claimed design.

1 Claim, 6 Drawing Sheets

FIG. 5

FIG. 6
